Parent case U.S. Appl. No. 29/212,958 filed on Sep. 10, 2004 to Watson, et al. entitled Air Duct Cleaner Tower and Cart Assembly; currently pending.

* cited by examiner

Primary Examiner—Louis S Zarfas

Assistant Examiner—Kathleen M Sims

(57) **CLAIM**

The ornamental design for an air duct cleaner tower and cart assembly, as shown and described.

DESCRIPTION

FIG. 1 is a front elevation view of an air duct cleaner tower and cart assembly incorporating the new design;

FIG. 2 is a rear elevation view of the air duct cleaner tower and cart assembly of FIG. 1;

FIG. 3 is a left elevation view of the air duct cleaner tower and cart assembly of FIG. 1;

FIG. 4 is a right elevation view of the air duct cleaner tower and cart assembly of FIG. 1;

FIG. 5 is a top plan view of the air duct cleaner tower and cart assembly of FIG. 1;

FIG. 6 is a bottom plan view of the air duct cleaner tower and cart assembly of FIG. 1;

FIG. 7 is an isometric view of the air duct cleaner tower and cart assembly of FIG. 1;

FIG. 8 is an exploded isometric view of the air duct cleaner tower broken away from the cart assembly of FIG. 1 for clarity of illustration;

FIG. 9 is a front elevation view of the air duct cleaner tower of FIG. 8;

FIG. 10 is rear elevation view of the air duct cleaner tower of FIG. 8;

FIG. 11 is a left elevation view of the air duct cleaner tower of FIG. 8;

FIG. 12 is a right elevation view of the air duct cleaner tower of FIG. 8;

FIG. 13 is a top plan view of the air duct cleaner tower of FIG. 8;

FIG. 14 is a bottom plan view of the air duct cleaner tower of FIG. 8;

FIG. 15 is a front elevation view of the cart assembly of FIG. 8;

FIG. 16 is a rear elevation view of the cart assembly of FIG. 8;

FIG. 17 is a left elevation view of the cart assembly of FIG. 8;

FIG. 18 is a right elevation view of the cart assembly of FIG. 8;

FIG. 19 is top plan view of the cart assembly of FIG. 8; and, FIG. 20 is a bottom plan view of the cart assembly of FIG. 8.

FIGS. 1 through 7 illustrate an air duct cleaner tower and cart assembly as assembled incorporating the new design. FIG. 8 illustrates the relationship of the air duct cleaner tower to the cart assembly. FIGS. 9 through 14 illustrate the design of the air duct cleaner tower by itself. FIGS. 15 through 20 illustrate the design of the cart assembly by itself.
